UNITED STATES PATENT OFFICE

ORVILLE E. PEASE, OF BALDWIN, NEW YORK, AND NORBERT G. JOSEPH, OF BOGOTA, NEW JERSEY, ASSIGNORS TO F. J. KLOES, INC., OF NEW YORK, N. Y., A CORPORATION OF NEW YORK

JOURNAL AND GUIDE BRACKET

Application filed August 14, 1928. Serial No. 299,526.

This invention relates to a journal and guide bracket, and for the purpose of exemplification is shown and described with a chain gear operated window awning.

The object of the invention is the production of a journal and guide bracket, by means of which the curtain rod of a chain gear operated window awning is supported and by which the sprocket chain of said awning is guided.

In the accompany drawings Fig. 1 represents a section as on the line 1, 1 of Fig. 6, exemplifying the journal and guide bracket with a chain gear operated window awning; Fig. 2 shows a perspective view of a portion of the hood of the awning; Fig. 3 is an enlarged section of Fig. 1 on the line 3, 3; Fig. 4 represents an enlarged section of Fig. 1 on the line 4, 4; Fig. 5 shows a section of Fig. 1 on the line 5, 5; Fig. 6 represents a front elevation of the chain gear operated window awning with the journal and guide bracket; Fig. 7 indicates an enlarged view of a portion of Fig. 6 and a section on line 7, 7 of Fig. 6; Figs. 8 and 9 represent enlarged perspective views of small portions of Fig. 6; Fig. 10 represents the elements indicated in Fig. 8 in a changed position; Fig. 11 shows an enlarged perspective view of a second form of the journal and guide bracket; Fig. 12 indicates a front view of Fig. 11 with some details added thereto and Fig. 13 indicates an enlarged section of Fig. 6 on the line 13, 13.

The chain gear operated window awning is represented as connected in place to the walls 20 of a window opening, and comprises a pair of angle irons 21 and 22, which are fastened in place by means of the bolts 23. The angle irons 21 and 22 are cut to form the clearance openings or spaces 24. The top ends of the angle irons 21 and 22 are connected by a hood indicated in its entirety by the numeral 25. The said hood comprises a pair of brackets located at its opposite ends. Each of said brackets comprises the vertical leg 28 and the horizontal leg 29, and the latter terminates in the nose end 30. A sheathing 31 of lead, preferably, covers the said brackets and upon the latter is pref-

erably located a sheathing 32 of copper, the outer edge of which latter has formed therewith a nose 33, which encloses the nose 30. Bolts 35 extend through the legs 28 and the angle irons 21 and 22 to secure the hood in place.

To the upper portion of the angle iron 21 is fastened the roller bracket 36 having the journal bearing 37 formed therein. To the upper portion of the angle iron 22 is pivoted the roller bracket 43, by means of the pivot pin 44. The latter bracket has formed therewith the slotted journal bearing 45. The bracket 43 is held in place by means of the screw 46, which engages a threaded opening in the angle iron 22.

The roller of the awning is indicated as comprising the tubular sleeve 48, having the plugs 49 and 50 tightly secured at its ends. A journal pin 51 extends from the plug 49. A sprocket chain wheel 52 is indicated with the boss 53, extending from one side thereof and the journal pin 54 from its other side. The boss 53 is tightly secured in the plug 50.

The journal and guide bracket is indicated in its entirety by the numeral 55, and comprises the arm 56, which has formed therewith the guide openings 57 and 58. The arm 56 has formed at one end thereof the flange 59. The latter is fastened to the angle iron 22, by means of screw bolts 60. A journal bracket is indicated in its entirety by the numeral 64. The latter bracket has formed therewith the flange 65, which is bolted to the angle iron 21 by means of the screw bolts 66. Each of the brackets 55 and 64 have extending therefrom a screw pivot 67 with the wing nut 68.

A U-shaped curtain supporting rod 69 has fastened to its ends the I brackets 70, which are hinged to the screw pivots 67. The curtain for the awning is indicated at 71 and has its upper end fastened to the sleeve 48 of the roller by being inserted in a slot thereof in the usual way, and the other end encircles and is fastened to the U shaped supporting rod 69.

At the lower portion of the angle iron 22 is indicated the adjustable crank handle plate 72. The plate 72 has formed therein the elongated openings 73 through which extend the

screw bolts 74, that are in threaded engagement with the angle iron 22 and adjustably clamp said plate 72 thereto. A screw pivot 78 having the head 79 extends from the plate 72 and is in threaded engagement therewith. A lock nut 80 is provided for the screw pivot 78 and bears against the plate 72. A sprocket chain wheel 81 has formed therewith the hub 82, and is journaled on the screw pivot 78. An operating handle 83 is provided with the socket end 84, which latter encircles the hub 82 and is fastened thereto by means of the set screw 85. A pawl 88 is pivoted to the plate 72 and is located to lock with the sprocket chain wheel 81.

To the walls 20 of the window opening are fastened the usual life belt catches 89, which extend through the openings or clearance spaces 24. A sprocket chain 90 engages the sprocket chain wheels 52 and 81 and extends through the guide openings 57 and 58 of the guide bracket 55. The openings 57 and 58 maintain the members of the chain 90 parallel to each other.

Referring to Figs. 11 and 12 a modified journal and guide bracket is indicated in its entirety by the numeral 93. The bracket 93 has formed therewith a flange 94 similar to flange 59 and an arm 97 at right angles thereto. At the outer end of said arm is formed the box shaped enclosure 95 with the walls 96, 98 and 98^a. The wall 96 and the arm 97 are connected by the angle shaped guide partition 99. A guide roller 100 is located in the enclosure 95 and has its ends pivoted in the wall 96 and the arm 97. The screw pivot 67, already described, extends from the arm 97 and is provided with its wing nut 68. In this instance the sprocket chain is indicated with the inclined member 101 and the member 102. The member 102 is guided between the end wall 98 and the partition 99, and the member 101 is guided over the guide roller 100. The guide bracket indicated in Figs. 11 and 12 is used in case the catches 89 are in the way and interfere with the operation of the sprocket chain.

To operate the mechanism of the window awning, the user disengages the pawl 88 from the sprocket chain wheel 81, and by means of the operating handle 83 turns the sprocket chain wheel 81. The rotations of the latter are transmitted to the sprocket chain wheel 52 through the sprocket chain 90, and thereby the curtain 71 is either roller on or from the roller having the sleeve 48, at the will of the user. When the curtain is located in the desired position, the pawl 88 is locked with the sprocket chain wheel 81.

Various modifications may be made in the invention and the present exemplification is to be taken as illustrative and not limitative thereof.

Having described the invention what we

desire to secure by Letters Patent and claim is:

1. A journal and guide bracket comprising an arm having openings adapted to guide the sprocket chain of a chain gear operated window awning, a pivot extending from the arm adapted to have hinged thereto one end of a curtain supporting rod.

2. A journal and guide bracket comprising an arm having formed at one end thereof a flange, a box shaped enclosure formed at the other end of the arm, an angle shaped guide partition in the box-shaped enclosure, and a guide roller in the said enclosure having its ends pivoted in said arm and in one of the walls of the enclosure.

Signed at the borough of Manhattan, city of New York, in the county of New York and State of New York, this 24th day of July, A. D. 1928.
